Inventor,
James Simcol Little,
By - B. Amigo, Atty.

UNITED STATES PATENT OFFICE.

JAMES SIMCOE LITTLE, OF WINDSOR, MELBOURNE, VICTORIA, AUSTRALIA.

CLIP FOR SHIRT COLLARS.

Application filed April 17, 1922. Serial No. 553,803.

To all whom it may concern:

Be it known that I, JAMES SIMCOE LITTLE, a subject of the King of Great Britain, residing at Windsor, Melbourne, Victoria, Australia, have invented new and useful Improvements in and Connected with Clips for Shirt Collars, of which the following is a specification.

My invention relates to means used for holding the loose ends or lapels of shirt collars which are sometimes retained by tapes, safety pins or other devices.

According to this invention, I provide a cylinder, that can be ornamented if desired, with each end closed. At one end of the cylinder I attach a wire that is fitted on its extremity with a hook or knob and through an opening in the other end of the cylinder I pass the shank of a second wire hook.

Within the barrel and surrounding the body of the second wire is a compression spring that is compressed when the hooked wire is drawn out of the barrel.

In order to prevent the loose wire from turning in its support, the opening in the cylinder end is made rectangular and the shank of the wire, where it passes into and out of the cylinder, is formed to correspond, in say, oblong cross section.

30 In the accompanying drawings—

Fig. 1 shows a well-known form of open spring clip and upon which my clip is an improvement.

Fig. 2 is a longitudinal section of my improved clip.

Fig. 3 is a side elevation of my invention.

Figure 4 is a transverse section on line 4—4 of Figure 2.

The wires 4 are finished at the outer ends 40 with a hook or knob for engaging the fabric

or a hole in the collar. One of the wires 4 is attached to the barrel or cylinder 7 while the other wire, which is longer, will pass well into the other end of the cylinder and be surrounded by the compression spring 6. 45 Means are upon the end of the longer wire to retain and seat one end of the spring, the other end of the spring bearing at the same time upon the end of the cylinder.

So that the movable wire shall not turn 50 in the cylinder opening, I make the opening rectangular and form the shank of the wire 4 to correspond. Thus, the fixed and movable hooks will always point the one way and this will facilitate the fixing of the clip 55 in the collar or material.

In operation, the movable wire hook is, preferably, first inserted in the collar, the clip being held at the opposite end. When properly hooked at the free end the clip is 60 pulled to extend the distance between the hooks, the spring 6 at the same time being compressed. After the fixed hook has been inserted, the clip can be released, when the reaction of the spring will draw the hooks 65 further into engagement and hold the same securely in position in the collar.

Having now described my invention what I claim as new and desire to secure by Letters Patent is:—

A clip of the kind indicated, comprising a barrel having a rectangular opening in one end, a hook fixed in the other end thereof, a spindle entering the barrel through and fitting in said opening, a hook on the outer end of the spindle and a compression spring about the spindle in the barrel. 75

In testimony whereof I have signed my name to this specification.

JAMES SIMCOE LITTLE.
